IGNITER DEVICE

Perl Lewis Bucy, Oklahoma City, Okla.

Application September 20, 1943, Serial No. 503,109

5 Claims. (Cl. 123—169)

This invention relates generally to the class of ignition devices and pertains particularly to an improved igniter designed for use in connection with internal combustion engines.

An object of the present invention is to provide an improved igniter having associated therewith means for introducing oxygen into the area within the igniter where the igniting spark is formed, whereby to produce a hotter flame and effect the complete oxidation of the fuel and the elimination of carbon deposits from the sparking or igniting chamber and the engine cylinder.

Another object of the invention is to provide an internal combustion engine sparking device of novel construction which is so designed that upon ignition of the charge the burning gases will be forced into the engine cylinder in the form of a flame jet so that the flame will be evenly distributed over the interior of the piston cylinder to effect a smooth even and complete combustion of the fuel.

Another object of the invention is to provide an igniter which is formed in such manner as to provide a relatively heavy or thick body of metal around the sparking chamber, which after being heated by the initial explosion of the fuel mixture, holds its heat so as to raise the temperature of the introduced oxygen and thereby bring about the more ready ignition of subsequent fuel charges.

The invention will be best understood from a consideration of the following detailed description taken in connection with the accompanying drawing, it being understood, however, that minor changes may be made in the details of construction so long as such changes do not depart from the spirit of the invention as expressed in the appended claims.

In the drawing—

Figure 1 is a view partly in elevation and partly in section of the device embodying the present invention.

Figure 2 is a vertical section through the device.

Figure 3 is a detail perspective, partly in section, of the cylindrical body.

Figure 4 is a detail section of the check valve.

Referring now more particularly to the drawing it will be seen that the device of the present invention comprises a ball or spherical body 10 which is divided into the two portions 11 and 12.

In the center of this spherical body there is formed a cylindrical chamber 13 which extends perpendicular to the opposed flat faces of the two halves of the body and which has one half in each of the body halves. In other words each

portion has formed therein and opening through the flat face thereof a circular chamber which when arranged coaxially with the chamber of the adjacent portion forms the complete cylindrical chamber 13.

Within the cylindrical chamber 13 there is fitted a cylindrical body 14 which has interposed between it and the wall of the chamber, a layer of asbestos 15.

Extending into each end of the cylindrical body 14 through a portion of the length of the body, is a threaded bore 16 and each of these bores at its inner end is tapered off to form a cone-shaped extension 17. The reduced inner ends of the bore extensions 17 are connected by the short longitudinally extending port or passage 18.

Each portion of the spherical body 10 has a threaded radial bore 19 which extends from the outer side of the body 10 into the adjacent end 20 of the chamber 13. These bores are coaxial with the chamber and with the threaded bores 16 of the cylindrical body 14 as shown.

When the two halves of the body 10 are disposed in assembled relation with the cylindrical body 14 within the chamber 13, they are secured together by the mounting stem 20 and the electrode stem 21.

The mounting stem 20 is in the form of a nipple which is threaded upon each end and which has the nut portion 22 intermediate its end to facilitate its application to the body and to the head of an engine. One of the threaded ends of this stem 20 is inserted into a threaded bore 19 and into the adjacent threaded bore 16 of the body 14 in the manner shown and a suitable shoulder 23 is provided at the inner end of the threaded portion of the stem, to bear against the wall of the body 10 so as to draw the adjacent end of the cylinder 14 firmly into position in the chamber 13.

The other end of the stem 20 is adapted for insertion into the usual spark-plug opening of a motor vehicle or other internal combustion engine cylinder head.

The stem 20 has an axial passage or bore 24, formed therethrough. This bore or passage is of tapered diameter from one end to the other. The opposing conical portions 17 of the bores 16 are of different lengths and the body 14 may be turned as desired so as to direct either of the bores 16 toward the engine combustion chamber and also the mounting stem 20 may have either of its ends engaged in a bore 16 so as to direct the wide or the narrow end of the bore 24 into the engine cylinder. These different operating positions for

the cylinder 14 and for the stem 20 are used for different operating conditions.

The electrode stem 21 has a threaded end adapted to extend through a bore 19 and into and have threaded connection in a bore 16, and this stem 21 is provided with a suitable shoulder 25 for engagement with the wall of the body 10 so as to draw the adjacent half or portion of the body 10 and the cylindrical body 14 tightly together. Thus by means of these stems 20 and 21 it will be seen that the two halves of the spherical body 10 are held tightly in assembled relation.

An asbestos gasket 26 is interposed between the two halves of the body 10 whereby, in association with the gasket or lining 15, compression leakage is avoided.

Extending axially through the stem 21 and suitably insulated therefrom, is the electrode 27 which extends at its inner end beyond the inner end of the stem 21 in which it is mounted. The inner end of the electrode 27 terminates in laterally directed points 28 and the length of the electrode is such as to bring these points into the adjacent conical portion 17 of the bore 16 in which the inner end of the electrode is secured, and into spaced relation with the wall of such conical portion so that a spark will be formed between each of points 28 and the adjacent bore wall.

The outer end of the electrode is suitably formed for the convenient attachment of a current conductor thereto.

One of the two sections of the body 10 has formed therethrough a lateral passage 29 which opens into the chamber 13. Joining or connected with this passage 29 is a lateral passage 30 formed in the cylindrical body 14, which passage 30 opens through the outer side of the body and also opens into the upper or shorter conical portion of the upper bore 16.

In the use of this sparking or firing head device there is provided a suitable receptacle 31 containing oxygen under pressure and from this receptacle a suitable conduit or tube 32 carries the oxygen to the passage 29, in which the other end of the conduit is connected as shown.

Within the passage 29 is a check valve 33 which opens toward the firing chamber which constitutes the aligned bores 16 in the cylindrical body 14. By this means oxygen may be admitted into the firing chamber when the pressure therein is lower than the pressure within the oxygen container 31 but when the pressure within the firing chamber exceeds that in the container 31 the valve 33 will prevent such back pressure entering the oxygen container.

As previously stated the mounting stem 20 is designed to be connected with the firing chamber in the cylindrical body 14 to have either the wide or the narrow end of the bore 24 opening into the firing chamber. When the use of gasoline in the engine fuel system is necessary the mounting stem will be connected with the body 14 as illustrated, that is, with the narrow end of the bore 24 opening into the firing chamber. When any other form of fuel oil is to be used the mounting stem is reversed so that the larger end of the bore 24 opens into the firing or ignition chamber and the smaller end opens into the motor cylinder.

In the use of this device the motor fuel is drawn into the cylinder in the usual manner but there is at the same time introduced into the cylinder and into the double conical firing chamber which constitutes the two conical inner portions of the bores 16, a portion of oxygen from the receptacle 31. As previously stated this oxygen flows into

the firing chamber when the pressure therein is below that in the container or receptacle for the oxygen. However when the engine piston is moving upwardly on its compression strokes the pressure within the firing chamber will be raised above that in the oxygen cylinder and the check valve will close thus preventing any of the fuel being forced back into the oxygen cylinder.

When the device is fired a portion of the fuel charge mixed with oxygen will be ignited in the double conical or "hour-glass" firing chamber and this will be discharged as a jet from this chamber and through the tapered bore 24 of the mounting stem into the engine cylinder where the remainder of the fuel will be ignited. Due to the jetting of the ignited fuel under high pressure into the engine cylinder the flame will be distributed through the cylinder and the fuel charge therein will be smoothly and progressively ignited in the manner most desirable for obtaining the maximum amount of power from the fuel. At the same time, due to the introduction of additional oxygen the fuel mixture will be completely consumed and there will be no carbon residue either in the firing chamber of the ignition device or in the engine cylinder.

I claim:

1. An ignition device comprising a body having an "hour-glass" shaped ignition chamber, an electrode extending into the upper end of such chamber and having spaced relation with the wall of the latter, a mounting stem connected with the lower end of said chamber and having a bore extending longitudinally therethrough and opening into the chamber, and a conduit means for introducing a combustion supporting gas into the ignition chamber.

2. An igniter device as set forth in claim 1, in which said conduit means enters the ignition chamber in the narrowest part thereof.

3. An igniter device comprising a body having a cylindrical chamber therein, said body being divided into two portions on a plane passing transversely through the cylindrical chamber, a cylinder body within the cylindrical chamber having threaded bores in the ends thereof, the bores being connected by a double cone-shaped ignition chamber, each of the said halves of said body having a bore extending into the adjacent end of the cylindrical chamber, a shouldered mounting stem extending through one bore and having one end extended through one of the last mentioned bores and having threaded engagement in a bore of the cylinder body, the mounting stem having a passage longitudinally therethrough opening into said ignition chamber, an electrode stem extending through the other one of the second mentioned bores and having threaded engagement in the adjacent bore of the cylindrical body, an electrode extending through the electrode stem into the ignition chamber, and means for introducing oxygen into said ignition chamber.

4. An igniter device as set forth in claim 3 in which said oxygen admitting means comprises a passage leading through the first body and through the cylinder body into the central part of the ignition chamber, and an inwardly opening check valve in said passage.

5. An igniter device as set forth in claim 3, in which the passage through said mounting stem is tapered throughout and the mounting stem is adapted to have either of its ends connected in a bore leading into the ignition chamber.
